US00D588147S

(12) **United States Design Patent**
Finlayson et al.

(10) **Patent No.:** **US D588,147 S**
(45) **Date of Patent:** **** Mar. 10, 2009**

(54) **SECURE PORTABLE DATA TRANSPORT AND STORAGE SYSTEM**

(75) Inventors: **James Finlayson**, Eugene, OR (US); **Reena B. Gordon**, Los Angeles, CA (US); **Roy Montibon**, Las Vegas, NM (US); **William A. Fox**, Rolling Hills Estates, CA (US)

(73) Assignee: **Photonic Data Security, LLC**, Torrance, CA (US)

(**) Term: **14 Years**

(21) Appl. No.: **29/302,582**

(22) Filed: **Jan. 18, 2008**

(51) **LOC (9) Cl.** **14-02**

(52) **U.S. Cl.** **D14/480.5**

(58) **Field of Classification Search** D14/436, D14/411, 384-385, 518, 348, 432-435, 299, D14/167, 402, 242, 356, 358, 496, 156, 240; 710/300-301; 439/131, 140-141; 361/684, 361/686

See application file for complete search history.

(57) **CLAIM**

The ornamental design for a secure portable data transport and storage system, as shown and described.

DESCRIPTION

FIG. 1 is an isometric view of the secure portable data transport and storage system, with the device in a closed configuration;

FIG. 2 is a right side elevation view of the device of FIG. 1;

FIG. 3 is a left side elevation view of the device of FIG. 1;

FIG. 4 is a front elevation view of the device of FIG. 1;

FIG. 5 is a rear elevation view of the device of FIG. 1;

FIG. 6 is a bottom plan view of the device of FIG. 1;

FIG. 7 is a top plan view of the device of FIG. 1;

FIG. 8 is an isometric view of the secure portable data transport and storage system, with the device in an open configuration;

FIG. 9 is a right side elevation view of the device of FIG. 8;

FIG. 10 is a left side elevation view of the device of FIG. 8;

FIG. 11 is a front elevation view of the device of FIG. 8;

FIG. 12 is a rear elevation view of the device of FIG. 8;

FIG. 13 is a bottom plan view of the device of FIG. 8; and,

FIG. 14 is a top plan view of the device of FIG. 8.
